UNITED STATES PATENT OFFICE.

CHARLES S. YOUNG, OF LOS ANGELES, CALIFORNIA.

ARCH SUPPORT FOR THE HUMAN FEET.

Application filed March 31, 1925. Serial No. 19,626.

The present invention relates to arch supports for the human foot and pertains more particularly to the arch support set forth in the patent to Young and Martin, 1,523,469, January 20, 1925.

In the arch support set forth in said patent there is provided an arched metal plate for the longitudinal arch and a pliant pad for the transverse arch.

It is one of the objects of the present invention to provide suitable coverings for both the said supports.

As stated in the above mentioned patent, the supports may be jointly enclosed in a suitable leather envelope, and it is another object of this invention to provide for practically anchoring both the longitudinal arch support and the transverse arch support to such envelope while providing for replacement of either or both the supports without danger to the envelope.

Another object of the invention is to protect the shoe and hose from actual contact with metal while retaining economical construction.

Still another object of the invention is to provide a combined transverse and longitudinal arch support which possesses the required flexibility in the metatarsal region.

Another object of the invention is to provide means for holding the metal arch support in substantially fixed position within the shoe while preventing the thin edges of the plate from coming in contact with the lining of the shoe.

Further objects and advantages of my invention will appear hereinafter.

I have illustrated my invention by the accompanying drawings, in which—

Figure 1 is a perspective view of one embodiment of the transverse arch support, such as shown in the above mentioned patent.

Figure 2 is a bottom plan of one complete embodiment of the present invention.

Figure 3 is a view in section seen on a line 3—3 of Fig. 2.

Figure 4 is a view in section seen on a line 4—4 of Fig. 2.

In carrying out my invention in the form shown in Figs. 1 to 4, inclusive, I employ the support 1, which is hereinafter termed a pliant pad for supporting the transverse arch. The pad 1 comprises two members, 14 and 15, respectively, attached to each other by suitable means, such as stitching 16, so that an intermediate space or slot 17 exists between

the posterior portions of the said members. The members 14 and 15 are comprised of leather or other suitable resilient material. It is understood that in special cases the member 14 is to be carved, moulded or otherwise shaped in conformance with the patient's foot. In cases where the support is to be sold in stores, a stock of various sizes and shapes of the pad 1 may be kept in stock.

In pad 1, member 15 is practically no larger than member 14, as shown in the drawings, although it may be enlarged if desired; the shape of member 15 having no bearing on the shape of member 14, or upon the condition of the patient's foot.

In the embodiment being described, there is provided a leather envelope composed of two sheets, 20 and 21, respectively, joined as by stitching (not shown); and providing an interior space 23, open at the forward end.

The longitudinal arch support, or metal plate 19 conforms in general outline to the outline of the rear part of the human foot and is inserted in the envelope. At the rear of the plate I provide a hob nail 23', which projects downwardly from the plate and extends through an opening 24 which is provided in the envelope. Said hob nail locates the plate within the envelope and keeps it properly positioned. To locate the entire unit 2 within a shoe (not shown) a shallow hole may be drilled in the shoe, in which hole the hob nail may be set. Member 20, of the envelope is provided with a transverse slit 25, through which the rear end of member 15 may project. Member 21 projects forwardly beyond the member 20 and overlies the pad 14.

To assemble the embodiment shown in Fig. 2, the metal plate is first placed in the envelope, then the pad 1 is inserted, so that the rear end of member 14 rests on the forward end of the metal plate, just as it does in the embodiment described in the above mentioned patent to Young and Martin.

The rear end of member 15 extends below the metal plate and thence through the slit 25, thus holding pad 1 suitably fixed with regard to the metal plate and the envelope. In cases where it is advisable to change either or both of the supports, or in cases where the restorative pressure is to be reduced, either or both of the supports may be removed for change or replacement. In some cases I find it advisable to withdraw

the metal plate, afterwards placing pad 1 back in the envelope so that the wearer is provided with a less rigid support for the anterior arch. Such support will be held 5 in proper position by the envelope alone, provided the envelope offers sufficient rigidity to hold itself in shape without the aid of the metal.

While I have shown and described specific 10 constructions of parts and specific arrangements of parts, I do not limit myself thereto, and I may alter same as I desire, or as occasion requires, without enlarging the scope of my invention within the appended 15 claims.

I claim;

1. In an arch support for the human foot, a plate, having a forward edge disposed so as to terminate about midway of the cavity 20 in the foot which is formed by the intersection of the longitudinal arch and the transverse arch, a pliant cover overlying said plate, a pliant member underlying at least the forward edge of said plate, a pad, shaped 25 for said cavity, overlying said forward edge of the plate and extending beyond such edge; said pad and said pliant member which underlies the plate being attached to each other.

2. In an arch support for the human foot, 30 a plate terminating forwardly in the metatarsal region, a flexible envelope embodying

upper and lower sheets completely enclosing said plate, and a pliant pad, shaped for the cavity formed by the intersection of the longitudinal and transverse arches, said pad 35 having a rear portion lying upon the upper surface of said plate with the forward portion projecting beyond said forward edge of the plate; said pad being attached to the said lower flexible sheet whereby the entire 40 arch support may bend along a transverse line adjacent the forward termination of the plate.

3. In an arch support for the human foot, 45 a plate terminating forwardly in the metatarsal region, a flexible envelope embodying upper and lower sheets completely enclosing said plate, and a pliant pad, shaped for the cavity formed by the intersection of the longitudinal and transverse arches, said pad 50 having a rear portion lying upon the upper surface of said plate with the forward portion projecting beyond said forward edge of the plate; said pad being detachably connected to said lower flexible sheet whereby 55 the entire arch support may bend along a transverse line adjacent the forward termination of the plate; the envelope being open at the forward end for insertion and removal of said pad.

CHARLES S. YOUNG.
